UNITED STATES PATENT OFFICE.

FRED A. ROWLEY, OF SPARTA, MICHIGAN.

ELECTRIC-TOOL HANDLE.

1,153,575.

Specification of Letters Patent. Patented Sept. 14, 1915.

Application filed June 12, 1912. Serial No. 703,320.

To all whom it may concern:

Be it known that I, FRED A. ROWLEY, citizen of the United States, residing at Sparta, in the county of Kent and State of Michigan, have invented certain new and useful 5 Improvements in Electric-Tool Handles, of which the following is a specification.

The present invention relates to certain new and useful improvements in electric tool 10 handles, and has for its object to provide a device of this character which embodies novel features of construction whereby the hand of the operator is effectively insulated and is at the same time prevented from slipping 15 forward and coming into direct contact with the machine.

A further object of the invention is to provide an electric tool handle of this character which is comparatively simple and inexpensive 20 in its construction, which can be readily placed in position or removed therefrom, and which will admit of a firm hold or grasp being obtained by the operator.

With these and other objects in view, the 25 invention consists in certain novel combinations and arrangements of the parts as will more fully appear as the description proceeds, the novel features thereof being pointed out in the appended claim.

For a full understanding of the invention, 30 reference is to be had to the following description and accompanying drawing, in which:—

Figure 1 is a perspective view of an electric tool handle constructed in accordance 35 with the invention. Fig. 2 is a longitudinal sectional view through the same, the plug being shown as withdrawn from the recess in the outer end of the handle. Fig. 3 is a 40 transverse sectional view on the line 3—3 of Fig. 2. Figs. 4, 5 and 6 are detail sectional views showing the construction of the plug which closes the recess in the end of the handle and locks the screw against rotation.

Corresponding and like parts are referred 45 to in the following description and indicated in all the views of the drawings by the same reference characters.

Specifically describing the present embodiment of the invention, the letter A designates the body portion of a handle, which may be formed of any suitable insulating material, such as hard rubber. This 50 body portion A of the handle comprises an outer end portion 1 which is shaped to form a convenient grip or hand hold, and an inner

enlarged portion 2 which fits directly against the tool and is separated from the grip portion 1 by means of an annular shoulder 3. The outer portion of the handle 1 is shown as tapered toward opposite ends thereof and suitably curved to admit of a strong and firm grasp being readily obtained upon the same. At the same time, it will be noticed that the annular shoulder 3 will serve to 60 prevent the hand of the operator from accidentally slipping forward upon the handle and coming into contact with the tool. The enlarged inner end 2 of the body portion A is recessed and has a nut 4 fitted therein, the 65 said nut being adapted to be rigidly applied to the tool. A screw 5 extends longitudinally through the body portion A and has the inner end thereof threaded in the nut 4, the outer end of the screw being formed with 70 a head 6 which is counter sunk within a recess 7 at the outer end of the handle. If desired, the inner threaded end of the screw 5 may extend beyond the nut 4 so as to engage 75 the tool and provide a means for securing the handle thereto. For the purpose of closing the recess 7 and at the same time locking the screw 5 against accidental rotation, a plug 8 of hard rubber or other insulating 80 material is employed. This plug 8 is slipped 85 in the recess 7 from the outer end thereof and is provided at its inner end with a rib 9 for engagement with the kerf of the screw 5, and at its sides with longitudinally disposed ribs 10 which engage corresponding 90 longitudinal grooves formed in the sides of the recess 7. The inner rib 9 thus interlocks with the head of the screw 5 so that the screw and plug cannot rotate independently 95 of each other, while the longitudinal side ribs of the plug engage the corresponding side grooves of the recess to lock the plug against rotation. In this manner the screw 5 is securely locked against accidental rotation and prevented from working loose. 100 After the handle has been mounted in position, the operator can grasp the outer end portion 1 thereof without danger of the hand coming into contact with any of the metallic portions of the handle or tool. 105

Having thus described the invention, what I claim as new and desire to secure by Letters Patent, is:—

The herein described tool handle including a body portion having a longitudinal 110 opening extending therethrough and provided at one end with a recess which com-

municates with the longitudinal opening and has longitudinal grooves in the side walls thereof, a screw extending through the longitudinal opening of the handle and having a head formed with a kerf and seated within the before mentioned recess at the end of the body portion, and a removable plug slid able within the recess, said plug being provided at its inner end with a trans-
verse rib adapted to engage the kerf of the

screw and being also formed at its sides with longitudinal ribs for engagement with the side grooves of the recess to lock the plug and screw against rotation.

In testimony whereof I affix my signature 15
in presence of two witnesses.

FRED A. ROWLEY.
